UNITED STATES PATENT OFFICE.

WILLIAM H. SAUTER, OF OWATONNA, MINNESOTA, ASSIGNOR TO THE CLEFTON COMPANY, OF OWATONNA, MINNESOTA, A CORPORATION OF MINNESOTA.

ACETYLENE GENERATOR.

Application filed July 25, 1919. Serial No. 313,282.

To all whom it may concern:

Be it known that I, WILLIAM H. SAUTER, a citizen of the United States, resident of Owatonna, county of Steele, State of Minnesota, have invented certain new and useful Improvements in Acetylene Generators, of which the following is a specification.

In the case of an acetylene generator of this type, the gas bell should be raised and 10 the generation of gas resumed before beginning the operation of pumping out the sludge in the bottom of the tank, the object being to prevent the entrance of air into the generator when the pump is attached and 15 during the pumping process assuming that the gas in the generator is practically exhausted and the bell has reached the limit of its downward movement. It often happens in practice that the user of the generator 20 through haste or forgetfulness will begin pumping without first raising the gas bell, resulting in the admission of air onto the tank and the service pipes.

The object of my present invention is to 25 provide means connected with the cap or cover of the pipe through which the sludge is removed, arranged in such relation to the gas bell that the bell must first be raised before the cap can be removed, thereby insuring the proper sequence of operation of 30 the parts of the generator preparatory to cleaning and refilling.

The invention consists generally in various constructions and combinations, all as 35 hereinafter described and particularly pointed out in the claims.

In the accompanying drawings forming part of this specification,

Figure 1 is a vertical sectional view 40 through an acetylene generator embodying my invention,

Figure 2 is a plan view of a portion of the generator, showing the device for closing the pipe to which the pump is attached, 45 Figure 3 is a detail view of a portion of the tank and the pipe, showing the cap lifted and swung to one side to allow the attachment of the pump to the tank.

In the drawing, 2 represents the water 50 chamber of the generator, 3 the hopper, 4 the gas bell submerged in the liquid seal in the annular chamber 5, 6 the auxiliary carbide hopper and 7 the gas filter communicating with the service pipe 8. 9 is the water 55 supply pipe for the tank 2 and 10 the agi-

tator arranged to sweep over the bottom of the tank. 11 is the pipe connected through the lower walls of the generator with the water chamber and extending to the surface of the ground. Through this pipe the sludge or 60 waste material in the bottom of the generator is removed. 12 is a cap or cover for the upper end of this pipe. 13 is a rod mounted in guides 14 on the inner wall of the generator and having a horizontal extension 15 at its upper end which passes outwardly 65 through a recess 15^a in the wall of the generator and is connected with the cap 12. The lower end of the rod 13 is provided with a loop 16 which projects in under the wall 70 of the gas bell.

When the gas bell is in its lowered position, the rod 13 cannot be raised, as the loop 16 will strike the lower walls of the bell and prevent upward movement of the rod and 75 the disengagement of the cap 12 from the pipe 11. It is necessary, therefore, before beginning the operation of removing the sludge from the tank to raise the bell by 80 hand so that the generation of gas as explained below will be resumed and when the bell has been raised sufficiently to allow the cap 12 to be removed from the pipe 11, the operator may then attach the pump to this pipe and remove the waste products 85 from the tank.

Referring to Figure 1 of the drawing, the lever 4^a for operating the valve 4^b is shown in the position it assumes when the lower blade of the valve is closed and the 90 upper blade open, these blades being in staggered relation on the valve stem, as shown in the patent to Claud J. Clefton, No. 1,133,618. Upon contact of the gas bell with the lever 4^a the weighted end will be lifted 95 and the valve turned on its axis to reverse the position of the blades. This will move the upper blade to the closing position and open the lower blade and at this point the carbide holder will be filled with carbide 100 when the auxiliary holder is removed.

Assuming now that the generator has to be cleaned out, it is desirable to first generate some gas to destroy the vacuum created by the removal of the water and sludge and 105 the operator should first, therefore, raise the bell and allow the lever 4^a to assume the position indicated in Figure 1, opening the upper blade of the valve and allowing a supply of carbide to drop into the chamber 110

above the lower blade. Then when the bell is released and drops down, as it will by gravity, no gas having been generated, it will contact with the lever 4^a, operate the 5 valve to move the lower blade to its open position, the upper blade to its closed position, and allow the carbide in the lower chamber to drop into the water and generate sufficient gas to fill the space created by the 10 removal of the water in the bottom of the generator. This gas pressure evidently will aid in excluding air from entrance into the generator during the operation of pumping out the water and sludge.

15 In Figure 1 I have shown the gas bell partially raised, with its walls lifted away from or out of engagement with the loop 16, but it will be understood that when the bell is at the limit of its downward movement 20 its walls will be close to the loop and will prevent the lifting of the rod 13 and the cap 12 until the bell has been raised sufficiently to permit such movement.

With this arrangement it is evident that 25 the user of the tank must follow the proper sequence of operation in refilling and instead of beginning the pumping operation immediately he must first raise the bell and allow the operation of gas generation to be resumed before access can be had to the pipe 30 leading to the generating chamber.

I claim as my invention:

1. The combination, in a gas generator, of a carbide hopper and a water chamber, a gas bell therefor and means actuated by the rise and fall of the bell for discharging the carbide from said hopper into said water chamber, a pipe connected with the lower portion of said water chamber 35 through which the sludge is removed, a cap for said pipe, and means connected with said cap preventing its removal from said pipe until said gas bell is raised.

2. The combination, in an acetylene generator, of a water chamber, a carbide hopper and a gas bell, means actuated by the rise and fall of said bell for discharging carbide from said hopper into said water chamber,

a rod mounted on the wall of said generator and having one end projecting under the 50 wall of said gas bell, a pipe connected with said water chamber and through which the sludge is removed, and a cap for said pipe connected with said rod and removable from said pipe only when said rod is raised 55 after the lifting of said gas bell.

3. The combination, in a gas generator of a carbide hopper and a water chamber, a gas bell, means actuated by the rise and fall of said bell for discharging carbide 60 from said hopper into said water chamber, a pipe for removing the sludge from said water chamber, means for closing the passage through said pipe and means co-operating with said closing means to prevent the 65 opening of said passage until said gas bell is raised a predetermined distance.

4. The combination, in a gas generator, of a carbide hopper and a water chamber, a gas bell therefor, means actuated by the 70 rise and fall of said bell for discharging carbide from said hopper into said water chamber, a draw-off means through which the sludge is removed from the generator, a 75 closing device for the draw-off passage, and means preventing the opening of said passage until said gas bell is raised.

5. The combination, in a gas generator, of a carbide hopper, and a water chamber, a gas bell therefor arranged to rise and 80 fall with the generation and discharge of the gas, a pipe connected with the lower portion of said water chamber through which the sludge is removed, a closing means for said pipe, and means preventing 85 the opening of said closing means and the removal of the sludge from said water chamber until said gas bell is raised to a predetermined point.

In witness whereof, I have hereunto set 90 my hand this 16 day of July 1919.

WILLIAM H. SAUTER.
